UNITED STATES PATENT OFFICE.

ROBERT E. JORDAN, OF CHICAGO, ILLINOIS, ASSIGNOR TO THE ALLBRIGHT-NELL COMPANY, OF CHICAGO, ILLINOIS, A CORPORATION OF ILLINOIS.

HAIR AND REFUSE REMOVER FOR DEHAIRING-MACHINES.

1,221,185.

Specification of Letters Patent.

Patented Apr. 3, 1917.

Application filed January 27, 1916. Serial No. 74,535.

To all whom it may concern:

Be it known that I, ROBERT E. JORDAN, a citizen of the United States, and a resident of the city of Chicago, in the county of Cook and State of Illinois, have invented certain new and useful Improvements in Hair and Refuse Removers for Dehairing-Machines; and I do hereby declare that the following is a full, clear, and exact description of the 10 same, reference being had to the accompanying drawings, and to the numerals of reference marked thereon, which form a part of this specification.

This invention relates to an improved type 15 of hog dehairing machine having associated therewith mechanism for recovering the hair and refuse scraped from the carcasses operated upon by the machine. In this invention the carcasses are first introduced into a 20 scalding tank and conveyed therefrom into the dehairing tank where the carcass is acted upon by dehairing mechanism, both while submerged and while partially submerged, the machine having a compartment at one 25 side thereof to receive the hair deposited in the machine from the carcasses.

It is an object of this invention to construct in combination with a hog dehairing machine a hair removing mechanism associated with the same whereby a flow of the 30 water is induced from the machine through said mechanism which operates to remove the hair to a point of discharge, allowing the water to drain therefrom during the removal 35 of the hair.

It is also an object of this invention to construct a machine adapted to dehair carcasses passed therethrough and provided with mechanism to receive the hair and 40 refuse scraped from the carcasses and carried by the flow of water within the machine to said mechanism, which operates to remove said hair and refuse, allowing the water to drain therefrom during the time of removal 45 thereof.

It is furthermore an object of this invention to construct in combination with a carcass dehairing machine mechanism to receive the hair and refuse removed from the carcasses comprising a conveyer moving over a 50 perforated partition, said conveyer acting to sweep the hair and refuse upwardly thereover, allowing the water to drain therefrom, finally discharging the hair and refuse 55 at a convenient point.

It is finally an object of this invention to provide in combination with a carcass dehairing machine means for efficiently removing the hair taken from the carcasses from the machine. 60

The invention (in a preferred form) is illustrated in the drawings and hereinafter more fully described.

In the drawings:

Figure 1 is a side elevation of a machine 65 embodying the principles of my invention.

Fig. 2 is an enlarged central longitudinal section taken therethrough, with parts shown in elevation.

Fig. 3 is a section taken on line 3—3 of 70 Fig. 2.

Fig. 4 is a fragmentary top plan view of the machine with parts broken away, and shown in section.

Fig. 5 is a detail section taken on line 5—5 75 of Fig. 4.

As shown in the drawings:

The machine consists of a long tank structure 1, having a partition 2, extending transversely thereacross near one end thereof affording a scalding compartment 3, on one side and on the other side a compartment 4, within which the scraping and dehairing mechanisms are mounted for operation upon carcasses passed through the machine. For this 80 purpose rollers 5, 6, 7, 8, and 9, respectively, are journaled transversely within the compartment 4, and trained thereover is a conveyer 10, having lags extending transversely thereacross and spaced upwardly to afford 85 clearance therebeneath and acting to contact the carcasses and thrust the same along. A curved perforated partition wall 11, is disposed near the forward end of the conveyer beneath the same and another similarly constructed partition wall 12, is disposed near the other end of said conveyer. Mounted in the scalding tank 3, and trained around rollers 13 and 14, respectively, is a small flight conveyer 15, which acts to elevate carcasses 90 from the scald tank over the partition 2, into the dehairing compartment 4.

A pair of dehairing mechanisms for the carcasses passed through the dehairing compartment 4, are provided, which as shown, 105 are exactly similar in construction and each consists of chains 16, trained about sprocket wheels 17 and 18, respectively, said chains having scraper blades 19, secured thereon, and one of said pair of dehairing mecha- 110

nisms disposed above said conveyer 10, in position over the curved perforated partition 11, and the other, over the other partition 12. Said respective sprocket wheels 17 and 18, are mounted in a frame 20, which is suspended from cables 21, which are trained over sheaves 22, mounted on the top wall of the tank structure 1, said cables having secured on their ends counterweights 23, so that adjusting movements of the dehairing mechanism may take place as the carcasses pass therebeneath. Additional dehairing means are mounted at two points beneath the upper flight of the conveyer 10, as clearly shown in Fig. 2, and comprise link belts 24, provided with scraper blades 25, said belts trained about rollers 26 and 27, respectively, one pair journaled beneath the upper flight of said conveyer 10, at the forward end thereof, and another pair near the rear end of said conveyer. As shown in Fig. 1, a sprocket wheel 28, is provided on the outer ends of the shafts for the upper sprocket wheels 18, and sprocket wheels 29, are secured upon the ends of the shafts on which the respective rollers 27, are mounted, and trained thereabout and about an idler roller 30, is a driving chain 31, a drive being imparted thereto from a drive wheel 32, secured on the same shaft with the sprocket wheel 29, at the rear end of the machine. A tension carriage of any suitable construction, denoted as a whole by the reference numeral 33, is suspended on said chain intermediate the sprocket wheel 28, and sprocket wheel 29, at the rear end of the machine to afford the requisite tension upon the chain. The respective conveyers 10 and 15, may be driven from any suitable source, not shown, but, however, are connected for simultaneous movement by a chain 34, trained about sprocket wheels 35 and 36, respectively, secured upon the shaft upon which the respective rollers 5 and 14, are mounted.

An auxiliary wall 37, is built at one side of the main tank structure 1, as clearly shown in Figs. 3, 4, and 5, to afford a hair receiving compartment, and said compartment communicates with the compartment 4, through narrow vertical passages 38 and 39, respectively, disposed at each end of the compartment 4, as clearly shown in Figs. 2 and 5. Mounted in inclined position within said hair receiving compartment is a perforated partition 40, with its lower end disposed adjacent the passageway 39, and its upper end adjacent the passage 38, so that the hair and refuse received with the water through the passage 39, may be moved upwardly on said partition by a scraper conveyer 41, provided with lags 42, which move over the upper surface of said partition.

The chains of said scraper conveyer 41, are trained about pairs of sprocket wheels 43, 44, and 45, respectively, of which the

pairs 43 and 44, are journaled above the upper edge of the wall 37, and the latter pair 45, of which are journaled within the lower rear end of the hair receiving compartment, as clearly shown in Fig. 5. A driving sprocket wheel 46, is secured upon the same shaft with the pair of sprocket wheels 43, for the purpose of imparting a drive to said scraper conveyer 41.

The operation is as follows:

The carcasses are introduced into the machine into the scalding compartment 3, and are then moved by the conveyer 15, upwardly over the partition 2, into the dehairing compartment 4. The carcasses then roll downwardly upon the curved partition wall or floor 11 beneath and into the field of operation of the first group of scrapers 17, and after a few moments of rotation therein, during which a dehairing operation proceeds, are thrust upwardly by one of the lags of the conveyer 10, over and in contact with the scraper blades 25, which move beneath the carcass end, of course, clearing the upwardly spaced lag of the conveyer 10. The carcasses then roll down beneath the second group of scrapers at the rear of the machine finally being thrust upwardly over the second group of scraper blades 25, and discharged at the rear of the machine. In each instance, the respective scraper blades 25, move beneath and, in fact, support the carcass which is thrust along by a conveyer lag, the latter, of course, being spaced upwardly an amount sufficient to permit clearance thereof beneath the lags as they move thereover. The hair and refuse removed from the carcasses is carried by the water through the long vertical passage 39, in the side of the compartment 4, and is then scraped upwardly over the perforated partition 40, and to a point of a discharge, the water of course draining through said perforated partition and passing out of the hair compartment through the vertical passage 38, and back into the compartment 4. The circulation of water from the compartment 4, through the passageway 39, into the hair removing compartment and from the hair removing compartment back through the passage 38, into the dehairing compartment, is induced by movement of the conveyer 41, longitudinally through said hair removing compartment.

I am aware that various details of construction may be varied through a wide range without departing from the principles of this invention, and I therefore do not purpose limiting the patent granted otherwise than necessitated by the prior art.

I claim as my invention:

1. In a device of the class described the combination with a dehairing machine, of a compartment at one side thereof, passageways affording communication between said

compartment and the interior of said machine, an inclined perforated partition in said compartment, and means moving thereover to receive the refuse passed into said

5 compartment and scrape the same upwardly over said partition to a point of discharge.

2. The combination with a dehauling machine comprising a tank, of a compartment at one side thereof, passageways affording 10 communication between said compartment and the interior of the tank to permit a circulation of water therebetween, and means in said compartment to remove the hair and refuse carried thereinto by said circulating 15 water.

3. In a device of the class described the combination with a tank of a hog dehauling machine, of a compartment at one side thereof, means permitting a circulation of water 20 between said tank and said compartment, a perforated drain water partition in said compartment, and means moving thereover to remove the hair and refuse deposited thereon to a point of discharge by the circulation of water through said compartment 25 and machine.

4. The combination with a carcass dehauling machine, of a compartment adapted to receive a flow of circulating water from 30 said machine and permit return of the water into said machine, means within said compartment straining the circulating water therethrough, and mechanism operating over said means to remove the hair and refuse 35 deposited thereon to a point of discharge.

5. In a carcass dehauling machine means to receive water circulated therefrom and to

return the same thereinto, and mechanism associated with said means for removing the hair and refuse from said circulating water 40 carried in said means.

6. A machine of the class described comprising a tank, a compartment built at one side thereof, an inlet to said compartment at one end thereof from said tank, an outlet 45 from said compartment at the other end thereof into said tank, an inclined perforated means mounted within said compartment to receive hair deposited thereon by the water circulating from said tank into 50 and through said compartment and returning through said tank, and means moving over said perforated means to remove the hair deposited thereon.

7. The combination with a hog scraping 55 machine embodying a tank, of a compartment built on said tank, a passage communicating into said tank from one end of said compartment, another passage communicating from said compartment at the 60 other end thereof into said tank, an inclined perforated partition mounted in said compartment between the respective passages leading therefrom into said tank, and a scraper mechanism operating thereover 65 to remove the hair deposited thereon to discharge the hair from said compartment.

In testimony whereof I have hereunto subscribed my name in the presence of two subscribing witnesses.

ROBERT E. JORDAN.
